REMOVABLE POWER DEVICE FOR EARTH-DRILLING MACHINES

Walter T. Caldwell, Enid, Okla., assignor to The George E. Falling Supply Company, Enid, Okla., a corporation of Oklahoma

Application April 6, 1938, Serial No. 200,388

9 Claims. (Cl. 255—22)

This invention relates to drilling rigs that are primarily intended for use in connection with core drilling operations, the drilling of shot-holes in seismic surveying, and the like.

5 In drilling rigs of this type, pressure is applied to the drill bit by means of a hydraulic device that is supported in line with the drilling string and movable from position when running in or removing the drilling string, inserting casing, 10 and other operations.

It is, therefore, a principal object of the present invention to provide an improved support for the hydraulic device whereby it may be readily moved into and out of operative position.

15 In accomplishing this and other objects of the invention, as hereinafter pointed out, I have provided improved details of structure, the preferred form of which is illustrated in the accompanying drawings, wherein:

20 Fig. 1 is an elevational view of a part of a drilling unit constructed in accordance with the present invention, parts of which are shown in section to better illustrate their construction.

Fig. 2 is a side elevational view of the drilling 25 unit, and

Fig. 3 is a plan view of a portion of the drilling unit, particularly illustrating the hydraulic power device.

Referring more in detail to the drawings:

30 Fig. 1 designates a platform of appropriate construction and which may be mounted upon the chassis of a motor vehicle. The rear central portion of the platform is provided with a substantially rectangular shaped opening 2, having 35 longitudinal guide rails 3 and 4 supporting a gear box or turntable 5 within the opening for rotating a Kelly rod 6 that is connected to the upper end of a drilling string 7 for rotating a drill bit 8, as in conventional practice.

40 Rotatably mounted in the gear box 5, on anti-friction bearings 9 and 10, is a drive sleeve 11 having an opening 12 therethrough corresponding to the cross-section of the Kelly rod. Fixed 45 on the sleeve is a beveled gear 13 that is rotated by means of a pinion gear having connection with a suitable prime mover (not shown) that is usually carried on the platform 1.

Also carried on the platform is a tower or mast 14, having upwardly converging standards 15 50 cooperating with rearwardly extending brace legs 16 to carry a crown block 17 for mounting the cable and tackle mechanism used in handling a drilling string, running in casing, and other operations incidental to drilling a bore-hole, the 55 tackle being connected with a swivel head 18

that is connected with the upper end of the Kelly rod, as in usual practice.

The structure thus far described specifically forms no part of the present invention, but is illustrated to better define the relation and purpose of the hydraulic power device used in controlling pressure applied to the bit 8.

The hydraulic power device includes a pair of spaced cylinders 19 and 20 which are provided with pistons 21 for effecting reciprocation of 10 piston rods 22 and 23 that are connected by a cross head 24, the piston rods extending through suitable packing glands 25 and 26 in the upper cylinder heads 27 and 28 of the cylinders. The lower ends of the cylinders are closed by heads 15 29 and 30 having pairs of ears 31—32 and 33—34 for a purpose later described.

The cross head 24 has a bearing 35 in which is rotatably retained a sleeve 36, having annular collars 37 and 38 engaging the respective upper 20 and lower faces of the bearing. Carried by the sleeve 36 is a clutch or chuck 39 that is equipped with suitable slips or jaws arranged to grip the Kelly rod so that the power pistons are effective in applying a downward pressure on the Kelly 25 rod or a lifting force thereon in controlling the weight on the drill bit.

The hydraulic pistons are operated by a pressure medium that is simultaneously admitted to the respective ends of the cylinders through ports 30 40 and 41 that are connected by conduits 42 and 43 having connection with a control valve 44 through flexible conduits 45 and 46. The control valve 44 also includes connections 47 and 48 respectively connected with the intake and discharge connections of a fluid pressure supply, such as a hydraulic pump (not shown).

When running in or withdrawing the drilling string, or when running casing into the bore-hole, it is necessary to move the hydraulic device 40 from over the turntable and I provide for swingingly mounting the hydraulic power device from the platform, as now to be described.

Supported on the platform, in substantial alignment with the outer sides of the hydraulic 45 cylinders and to the rear of the turntable, are brackets 49 and 50 comprising vertical, post-like portions extending upwardly from the platform to a point in substantially horizontal alignment with the top of the cylinders. The base of the 50 post portions are provided with laterally extending flanges 51 that are secured to the platform by fastening devices, such as bolts 52, extending through the flanges and through slotted openings 53 in the platform, as best shown in Fig. 2. 55

The post portions of the brackets are braced from the platform by bars 54, having flanged ends 55 that are likewise secured to the platform by fastening devices, such as bolts 56, extending through the flanges 55 and through registering slots 57. The bars 54 are also connected with the post portions of the brackets by bars 58. Pivotedly connected with the heads of the cylinders, by cap screws or the like 59, are links 60 extending rearwardly therefrom and pivotally connected with the post portions of the brackets by bolts 61 extending through the ends of the links and through the post and brace bar portions of the bracket, as best shown in Fig. 3. Connected by the ears 33 and 34, previously mentioned, are links 62 which extend rearwardly of the platform in parallel relation with the links 63 to pivotally connect the brackets 63 that are adjustably mounted on the platform in the same manner as the brackets previously described, the links being secured to the brackets by bolts 64 and to the ears by pivot pins 65.

When the hydraulic mechanism is in the operative position illustrated in Fig. 2, the links 62 are secured to the platform by J bolts 66, having their hook portions 67 engaged over the upper edges of the links and their threaded shanks 68 extending through suitable openings 69 in the platform and secured by nuts 70. When the hydraulic device is to be shifted away from the sides of the turntable, the J bolts are removed and a tackle mechanism is attached to the upper link 60. The tackle mechanism includes a cable 71 operating over a pulley 72 on the legs 16 of the mast, and which is wound on a windlass or the like (not shown), that is also carried on the platform. By winding up the cable the upper links 60 are swung on their pivot 61 to the opposite sides of the brackets 49 and 50, the hydraulic devices moving in an arc from the operative position to the dotted line position shown in Fig. 2.

From the foregoing it is obvious that I have provided an improved supporting mechanism for the hydraulic power device whereby it is moved out of the way when drilling operations are suspended to permit removal or running in of the drilling string, or to case the bore-hole, as in conventional drilling practice.

What I claim and desire to secure by Letters Patent is:

1. In combination with a rotating mechanism, a support carrying said rotating mechanism, a power device including a pair of cylinders disposed on opposite sides of the rotating mechanism, brackets on the support and spaced from the rotating mechanism, and spaced pairs of links connecting the cylinders with said brackets whereby the power device is adapted to be moved from position relatively to the rotating mechanism to a substantially corresponding position on the opposite side of said brackets.

2. In combination with a rotating mechanism, a support carrying said rotating mechanism, a power device including a pair of cylinders disposed on opposite sides of the rotating mechanism, brackets on the support and spaced from the rotating mechanism, spaced pairs of links connecting the cylinders with said brackets whereby the power device is adapted to be moved from position relatively to the rotating mechanism to a substantially corresponding position on the opposite side of said brackets, and means for anchoring the power device to the support when in said first mentioned position.

3. In combination with a turntable, a Kelly rod

rotatable by the turntable, a power augmenting device connected with the Kelly rod, and means for swingingly supporting the power augmenting device for movement into and out of operative position with respect to the turntable, including a pair of brackets and upper and lower links connecting the power augmenting device with the brackets.

4. In combination with a turntable, a platform supporting the turntable and a Kelly rod rotatable by the turntable, a hydraulic power device including a pair of hydraulic cylinders disposed on opposite sides of the turntable, means for releasably connecting the power device with the Kelly rod, and means for swingingly supporting the hydraulic power device for movement into and out of operative position with respect to the turntable, including a pair of brackets located on the platform rearwardly of the cylinders, and upper and lower links pivotally connecting the respective cylinders with the brackets.

5. In combination with a platform, a mast supported on the platform, a turntable carried by the platform and a Kelly rod rotatable by the turntable, a hydraulic power device including a pair of cylinders vertically disposed on opposite sides of the turntable, pistons in the cylinders, rods connected with the pistons, a cross head connecting the rods, means on the cross head for releasably engaging the Kelly rod, a pair of brackets located on the platform rearwardly of the cylinders, upper and lower links pivotally connecting the respective cylinders with the brackets, and means connected with the mast for swinging said hydraulic power device from operative position relatively to the turntable to an inoperative position at the opposite sides of said brackets.

6. In combination with a platform, a mast supported on the platform, a turntable carried by the turntable, a hydraulic power device including a pair of cylinders vertically disposed on opposite sides of the turntable, pistons in the cylinders, rods connected with the pistons, a cross head connecting the rods, means on the cross head for releasably engaging the Kelly rod, a pair of brackets located on the platform rearwardly of the cylinders, upper and lower links pivotally connecting the respective cylinders with the brackets, a pulley carried by the mast at a point substantially above said brackets, and a cable operating over the pulley and having connection with the power device for bodily moving the power device from operative position relatively to the turntable to an inoperative position on the opposite sides of said brackets.

7. In a drilling rig, a platform, a power augmenting device including a pair of spaced cylinders, pistons slidable in the cylinders, rods connected with the pistons, a cross head connecting the rods, means on the cross head for grippingly engaging a drilling string, a pair of brackets located on the platform in spaced relation with the cylinders, and parallel links respectively connecting the upper and lower ends of the cylinders with the brackets whereby the power augmenting device is adapted for bodily swinging movement from one side of the brackets to the other.

8. In combination with a platform, a power augmenting device, spaced brackets on the platform, links respectively connecting upper and lower ends of the brackets with spaced portions of the power augmenting device to swingingly

support the power augmenting device for bodily movement into and out of an operative position on the platform, and means for anchoringly connecting the power device with the platform when the power device is in operative position.

9. In an apparatus of the character described, a platform, a power augmenting device, means for swingingly supporting the power augmenting device for bodily movement into and out of operative position on the platform including a pair of

brackets, pairs of upper and lower links connecting the power augmenting device with the brackets whereby the power augmenting device is kept in substantially perpendicular position during said transposition, and fastening devices for anchoring selected links to the platform when the power augmenting device is in operative position on the platform.

WALTER T. CALDWELL.
